UNITED STATES PATENT OFFICE.

HENRY HARRIS PAYZANT, OF EVERETT, WASHINGTON, ASSIGNOR TO WOOD CONVERSION COMPANY, OF CLOQUET, MINNESOTA, A CORPORATION OF DELAWARE.

DISTRIBUTING HOOD.

Application filed May 28, 1925. Serial No. 33,408.

This invention relates to an improved distributing hood adapted to be used in the manufacture of resilient masses or bodies of fibrous material in the form of sheets, layers or batting, and especially adapted to be used in the manufacture of the product known as wood cotton.

One method which has been employed in making wood cotton consists in separating wood into a flocculent mass by shredding, and depositing the separated fibers onto a belt or screen conveyor so that they arrange themselves in a loose, resilient, heterogeneous mass. The fibers are treated with an adhesive either before they come in contact with the conveyor or immediately thereafter. Heretofore the fibers have been deposited upon the conveyor by sifting them through one or more screens arranged at the bottom of a bin or receptacle into which the wood fibers are continuously fed. This method of depositing the fibers upon the conveyor is not entirely satisfactory for the reason that the screens tends to become clogged and considerable time is wasted in cleaning the screens and readjusting them so that the operation can be continued.

The present invention provides means whereby loose material, such as wood fibers, can be deposited upon a traveling surface in an even layer without employing screens or other devices which readily become clogged or disarranged. In general, I accomplish this result by providing a supply pipe through which the fibrous material is blown, and providing a distributing hood at the open end of the supply pipe. This hood is provided with an adjustable deflecting member arranged so that the fibrous material discharged from the supply pipe is deflected by this member and distributed to any desired extent upon the surface of the conveyor.

The numerous advantages of my invention over the devices ordinarily employed for the purpose of depositing fibrous material upon a conveyor, will be apparent upon considering the following detailed description, which is to be taken in conjunction with the accompanying drawings, in which—

Figure 1 is a front elevation of my improved distributing hood and a section of a screen conveyor.

Figure 2 is a side elevation of the dis-

tributing hood and conveyor shown in Figure 1, and

Figure 3 is a fragmentary sectional view of certain details of construction.

In Figures 1 and 2 I have illustrated a conveyor 1 of any common type such as the screen conveyors used in the manufacture of wood cotton or other resilient masses or bodies of fibrous material. Loose fibrous material 2 is supplied to the conveyor 1 through a pipe 3 and distributing hood 4. The pipe 3 may consist of any ordinary piping through which fibrous material can be blown. The lower end of this supply pipe is preferably bent into a horizontal position and the hood 4 is secured to this end of the supply pipe so as to extend down at substantially right angles thereto. The hood 4 is preferably fan shaped, as illustrated in Figures 1 and 2, and extends down into close proximity to the conveyor 1.

An adjustable deflecting member 6 is provided near the apex of the hood 4 and is adapted to swing into the interior of this hood so as to restrict the passage leading downward from the supply pipe 3. The projecting end of the supply pipe 3 is closed by an abutment shown at 5, the opening in this pipe being provided at the bottom of the end thereof, facing downward into the hood 4. The deflecting member 6, which is preferably provided with a curved edge, is hinged to the hood 4 at a point substantially in line with the opening in the supply pipe 3. An opening is provided in the side of the hood 4 in the immediate vicinity of the hinged member 6 so as to accommodate an adjusting rod 7 by means of which the position of the deflecting member can be changed. The deflecting member 6 can be hinged to the upper edge of the opening provided in the side of the hood 6 and the adjusting lever 7 can be provided with teeth 8 adapted to engage the lower edge of this opening. The deflecting plate 6 can be locked in any desired angular position by bringing the toothed lever 7 into contact with the lower edge of the opening in the side of the hood 4.

The material discharged from the pipe 3 strikes against the vertical abutment 5 and the deflecting plate 6, and falls in a spray onto the conveyor 1. The character of this spray of material is determined by the posi-

tion of the deflecting plate 6. By moving the adjusting rod 7 in, and thus further restricting the passage within the upper part of the hood 4, the fibrous material can be spread to a greater extent. In fact the layer of material deposited upon the conveyor 1 can be made thicker along the edges than in the center by moving the deflecting plate 6 to an extreme inner position.

10 I am aware that various changes in the details of construction of my distributing device can be made without departing from the scope of the invention, which is not limited to the particular embodiment illustrated and described, but includes such modifications thereof as fall within the scope of the appended claims.

I claim:

1. A device of the type described comprising a supply pipe, a distributing hood associated therewith, said hood having an opening in the side thereof, and a member having a curved edge, said member being hinged to said hood along one edge of the opening in the side thereof and adapted to swing into the interior thereof.

2. A device of the type described comprising a supply pipe, a distributing hood associated therewith, said hood having an opening in the side thereof, a deflecting member having a curved edge hinged to said hood along one edge of the opening in the side thereof and adapted to swing into the interior thereof, and a toothed member connected to the free end of said deflecting member and arranged so that said deflecting member can be locked in any desired position by bringing the toothed member into engagement with the edge of the opening in the side of said hood.

3. A device of the type described comprising a supply pipe, a fan shaped distributing hood associated therewith, said hood having an opening in the side thereof, and adjustable means associated with said hood near said opening for determining the distribution within said hood of material supplied by said pipe.

4. A device of the type described comprising a supply pipe, a fan shaped dis-

tributing hood associated with the open end thereof and at right angles thereto, said hood having an opening in the side thereof, and adjustable means associated with said hood near said opening for regulating the velocity and distribution of material within said hood.

5. A device of the character described comprising a supply pipe, a fan shaped distributing hood fixed to the open end of said supply pipe and extending downward at substantially right angles to this end of the supply pipe, said hood having an opening in the side thereof and near the top thereof, a deflecting member having a curved edge hinged to said hood along one edge of the opening in the side thereof and adapted to swing into the interior of said hood, and a toothed member connected to the free end of said deflecting member and arranged so that said deflecting member can be locked in any desired position by bringing the toothed member into engagement with the edge of the opening in the side of said hood.

6. In combination with a travelling surface and a supply pipe, a fan shaped distributing hood associated with the open end thereof and at right angles thereto, and having an adjustable, internal, deflecting plate so placed within said hood near its intake throat as to regulate the velocity and distribution of material within the said hood that discharge of the material is effected in a layer of any desired width and thickness upon said relatively travelling surface.

7. A device of the type described, comprising a supply pipe, a distributing hood associated with the open end thereof, said hood having an opening below and on the opposite side thereof to the supply pipe entrance, and a deflecting plate having one edge hinged to said hood above said opening and adapted to swing either into deflecting position within the hood or into coincidence with the wall of the hood, thereby closing said opening and leaving the interior of said hood free of all obstruction.

In testimony whereof I affix my signature.

HENRY HARRIS PAYZANT.
